DESIGN FOR AN OUTBOARD MOTOR FOR BOATS

John R. Morgan, Oak Park, Ill., assignor to Sears,
Roebeck and Co., Chicago, Ill., a corporation
of New York

Application July 30, 1937, Serial No. 70,747

Term of patent 7 years

To all whom it may concern:

Be it known that I, John R. Morgan, a citizen of Guatemala, residing at Oak Park, in the county of Cook and State of Illinois, have invented a new, original, and ornamental Design for an Outboard Motor for Boats, of which the following is a specification, reference being had to the accompanying drawings, forming part thereof.

Figure 1 is a side elevation of an outboard

motor for boats embodying the features of the invention.

Fig. 2 is a front elevation of the same.

Fig. 3 is a rear elevational view of the same.

Fig. 4 is a top plan view thereof.

I claim:

The ornamental design for an outboard motor for boats, substantially as shown.

JOHN R. MORGAN.
